ATOMIZER

Harold A. Roselund, Dayton, Ohio, assignor to
 C. W. Harwin Inc., Dayton, Ohio, a corporation
 of Ohio

Application May 20, 1950, Serial No. 163,143

3 Claims. (Cl. 299—88)

1

This invention relates to an atomizer and more particularly to a pocket or purse type of perfume atomizer.

A number of problems are present in the design of perfume atomizers of this type that are not present in other types of atomizers. Thus, in a purse type of atomizer it is very important to provide a compact atomizer which is easy to refill and which may be operated by one hand. It is recognized that a large number of perfume atomizers have been devised from time to time, but these have not met all the above requirements or have had other objectional features, such as being too expensive.

It is an object of this invention to provide an atomizer which not only meets the above-mentioned requirements but which has numerous additional desirable features. Thus, another object of this invention is to provide an atomizer which has a large perfume reservoir having a large fill cap which serves as the one end wall of the atomizer.

Still another object of this invention is to provide an atomizer which dispenses the desired amount of perfume in a fully atomized condition.

Still another object is to provide an improved mechanical construction whereby the atomizer is exceptionally durable and yet inexpensive to manufacture.

Other objects and advantages reside in the construction of parts, the combination thereof and the mode of operation, as will become more apparent from the following description.

In the drawing:

Figure 1 is a vertical sectional view showing the atomizer in its fully collapsed position;

Figure 2 is a view similar to Figure 1 but showing the atomizer in its fully extended position;

Figure 3 is a horizontal sectional view taken substantially on line 3—3 of Figure 1;

Figure 4 is a perspective view of the atomizer; and

Figure 5 is a perspective view, with parts broken away, showing the atomizer in a carrying case.

Referring now to the drawing wherein there is shown a preferred embodiment of the invention, reference numeral 10 designates the main casing which is cylindrical in shape and serves as an outer housing for an inner housing 11 which constitutes a combined perfume chamber and piston. A cap 12 is threaded to the lower end of the outer housing 10 and serves as a closure for the lower end of the pumping chamber which is thus formed between the inner and outer hous-

2

ings. A suitable gasket 14 has been provided, as shown, for providing a tight seal between the cap 12 and the outer housing 10.

The inner housing 11 has its upper end closed by means of a cap 16 and the sealing gasket 18. An inner lining 13 is secured within the inner housing 11 and has its bottom wall and a portion of its side wall spaced from the inner wall of the housing 11 so as to form an air passage 23 for a purpose to be explained hereinafter. The lower end of the combined perfume chamber and piston 11 serves to support a pumping element or piston seal 20 which is used in compressing air for aspirating perfume.

15 A spring 22 urges the inner housing 11 upwardly within the outer housing 10 whereby a pumping action may be produced merely by holding the end of the atomizer between one's fingers and applying pressure to the opposite end of the atomizer so as to compress air within the lower portion of the outer housing 10. As pressure is applied against the ends of the atomizer, the air trapped in the lower portion of the outer housing 10 will be caused to pass upwardly through the central passage 24 formed in the cap screw 26, from whence the air will travel through the passage 28 which leads to a circular outlet opening 32 which surrounds the perfume outlet tube section 33. The upper end of the passage 28 constitutes a plenum chamber which serves to insure uniform flow of air through all portions of the circular outlet opening 32. The circular outlet opening 32 cooperates with the outer end of the tube section 33 to form a vacuum in the tube section 33, creating a vacuum in this tube 33 to withdraw perfume. The perfume is conveyed to the outlet tube section 33 through the fluid tube or pipe 30 which has its lower end arranged adjacent the bottom of the inner housing 11 and which has its upper or outlet end connected to the tube section 33. The tube section 33 may be formed by reducing the diameter of the end of the main tube or pipe 30 or it may be formed as a separate piece inserted into the upper end of tube 30. The section 33 terminates approximately .006 inch beyond the outer wall of the inner housing 11, as shown.

40 The size and arrangement of the opening 32 is such that the escaping air serves to aspirate perfume from the perfume chamber via the tube 33 and to atomize the perfume thus picked up by the air. A vent 34 allows air to enter the upper portion of the inner housing 11 when the atomizer is in its extended position. When the atomizer is 45 in its fully collapsed position, the vent 34, the

50

55

tube 30, and the air passage 32 are all sealed by means of the resilient sealing pad 36 which is held in place within the embossed cavity 38 formed in the side wall of the outer housing 10 and which projects slightly beyond the cavity so as to firmly seal the vent 34 and the tube section 33.

In order to prevent relative rotation between the outer housing 10 and the inner housing 11, the outer housing 10 is provided with an inwardly extending embossed portion 40 which cooperates with a longitudinally extending groove 42 formed in the one wall of the inner housing 11, as best shown in Figure 3. By virtue of this arrangement, the sealing member 36 will always properly line up with the outlet of the tube section 33 and the vent 34. The embossed portion 40 also serves as a stop for limiting the outward movement of the inner housing 11 through its coaction with the washer element 44 which is firmly held against the bottom wall of the inner housing 11. Furthermore, the groove 42 provides clearance for the projecting sealing pad 36.

Since atomizers of this type are adapted to be carried by women in their purses, it is important that they be very compact and that they occupy the minimum amount of space when not in use. In the atomizer shown herein, the bottom cap 12 has riveted thereto one section 50 of a snap fastener. The section 50 supports a snap ring 52 which is adapted to snap over the bottom end of a complementary snap fastener member 54 which is held in fixed relation relative to the bottom wall of the inner housing 11 by means of the cap screw 26. The snap element 54 is provided with the usual mounting flange 56 which is used for holding the washer element 58 against the piston sealing member 20. By virtue of this snap arrangement, the atomizer can be stored in its fully collapsed position when the atomizer is not in use, even though the spring 22 continuously biases the inner housing 11 outwardly relative to the outer housing 10. The amount of force required to engage and disengage the snap is sufficiently great so that anyone using the atomizer can pump it up and down repeatedly by the application of ordinary pressure, but in order to engage the snap element, it is necessary to exert an additional pressure.

In Figure 5 of the drawing I have shown the atomizer disposed within a specially constructed carrying case 60. Atomizers sold in cases like the case 60 do not need to be provided with the snap elements 50 and 54, as the end walls of the case 60 are designed to hold the atomizer in its collapsed position while not in use. The case 60 is also useful with atomizers provided with the snap elements for those who do not wish to or fail to push the ends of the atomizer together far enough to engage the snap elements.

It will be noted that the case 60 consists of two halves hinged together at 62. Each end wall of the lower half consists of a narrow flange 64 which leaves the greater part of the ends of the atomizer accessible for engagement by one's fingers when removing the atomizer. The top half of the casing, which serves as a cover, is provided with end walls 66 which extend down to the end flanges 64 so as to completely close the ends of the case when the cover is shut. The hinge 62 is preferably of the well-known type which automatically biases the cover either into

the fully closed position or the fully open position. Since the details of the construction of the hinge forms no part of this invention and since hinges of this type are well-known, it will not be described in detail.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. In a pocket type of perfume atomizer, an outer cylindrical housing, an inner cylindrical housing telescopically mounted within said outer housing, said inner housing having an embossed longitudinally extending groove, a nozzle carried by said inner housing and having its outlet arranged beyond the outer surface of said inner housing adjacent said outlet, an inwardly directed embossed portion on said outer housing seated in said groove and arranged in alignment with said nozzle, an outwardly embossed portion on said outer housing, a nozzle sealing means supported within said outwardly embossed portion for engaging the outer end of said nozzle in one relative position of said housings, and means for venting said inner housing including an opening in the one wall of said inner housing arranged adjacent said nozzle so as to be closed by said nozzle sealing means.

2. In a pocket type of perfume atomizer according to claim 1, wherein means are provided for securing the outer housing and the inner housing, said means including a snap fastener having one portion thereof secured to one end of said outer housing and having its other portion secured to said inner housing.

3. In a pocket type of perfume atomizer according to claim 1, wherein the outer housing functions as a cylinder and the inner housing functions as a piston slidable within said outer housing, the two housings cooperating to form a pumping chamber, wherein resilient means are provided, said resilient means including a spring urging the piston outwardly, and wherein a snap fastener secures the two housings together, said snap fastener having one portion thereof secured to one end of said outer housing and having its other portion secured to said inner housing, said snap fastener being strong enough to overcome said spring.

HAROLD A. ROSELUND.
